UNITED STATES PATENT OFFICE.

BERNARD H. SKELLY, OF BRIDGEPORT, CONNECTICUT, ASSIGNOR TO GREENE, TWEED & CO., OF NEW YORK, N. Y., A CORPORATION OF NEW YORK.

INTERMITTENT OPERATING MECHANISM FOR LUBRICATORS.

1,160,539.

Specification of Letters Patent. Patented Nov. 16, 1915.

Application filed April 21, 1915. Serial No. 22,810.

To all whom it may concern:

Be it known that I, BERNARD H. SKELLY, a citizen of the United States, residing at the city of Bridgeport, county of Fairfield, 5 State of Connecticut, have invented certain new and useful Improvements in Intermittent Operating Mechanism for Lubricators; and I do declare the following to be a full, clear, and exact description of the 10 invention, such as will enable others skilled in the art to which it appertains to make and use the same.

This invention relates to force feed lubricators such as are commonly used in connection with large engines, the oil being distributed from the lubricator to the cylinders or to any desired part of the engine.

This improvement aims to insure either a minimum or a maximum oil feed irrespective of the length of the stroke of the engine or the rapidity thereof, this being brought about by positive adjustments as well as by a clutch feed whereby the shaft of the lubricator will be revolved intermittently in one 25 direction only.

This invention has nothing whatever to do with the cam slide which is operated by the shaft of the lubricator or with the piston for forcing the oil from the reservoir 30 out through the supply pipe to the lubricator, nor does this invention pertain to the check valves which govern the supply system of the oil, and I therefore have not illustrated in detail nor will I describe the construction of the lubricator except only in so 35 far as it has immediate relation to my improvement.

In all lubricators of the type illustrated, there is a shaft that is revolved intermittently to cause the piston to operate to deliver the oil into the supply pipe of the lubricator, and my invention mainly relates to this intermittent revolution of the shaft, and in order that there may be no interruption 40 in the supply of oil my improvement furthermore relates to the installation of the gage glass any breakage of which will be immaterial so far as the uniform and regular supply of oil is concerned.

50 Referring to the accompanying drawing Figure 1 is a front elevation of a lubricator constructed in accordance with my improvement, Fig. 2 a detail broken elevation of the feed block with the crank removed. Fig. 3 is a detail broken view of the inner face of

the crank. Fig. 4 is a detail view of the rear of the driving block and detent disk. Fig. 5 is a detail broken elevation of the feed block with the driving block and parts carried thereby removed, and Fig. 6 is a detail view, partly in section and in plan, of the driving block and parts carried thereby.

Similar numerals of reference denote like parts in the several figures of the drawing.

1 is the oil reservoir, 2 the feed block, 3 the cam slide, 4 the piston having an elongated opening 5 within which extends a finger 6 from the cam slide, and 7 is a long screw driven through the top of the piston and extending into the opening 5 and provided with a lock nut 8. All the parts above referred to are old and well known and are common to force feed lubricators.

The screw 7 is adjusted so as to extend more or less into the opening 5 for the usual purpose of regulating the effective stroke of the piston which is caused by the impact of the finger 6 that extends from the cam slide, and this is the ordinary way of controlling the action of this piston and has nothing to do with the present invention.

9 is the shaft of the lubricator whose revolution effects the movements of the cam slide and consequently the movements of the piston, and I will first describe the mechanism 35 which I employ for intermittently rotating this shaft.

10 is what I term the driving block whose hub 11 is splined on the shaft 9, this driving block having a web portion 12 extending from the hub to the rim of the block, whereby the interior of the latter is divided into two recessed portions 13, 14, the former of which is comparatively shallow while the latter is comparatively deep.

Within the recess 14 and loosely journaled around the hub 11 is the driving clutch member 15 which has four substantially equidistant stubs 16 which extend radially from the periphery of the member 15, so as to provide four separate elongated ways *a*, *b*, *c*, and *d*.

The side boundary walls of these ways are the inner surfaces of the rim of the driving block and the outer perimeters of the member 15, and in the instance of two of these ways *a*, *c*, that are diametrically opposite, the perimeters of the member 15 are eccentrically disposed so as to cause these ways to be tapering at one end, and within 110

these ways *a*, *c*, are comparatively long loose rolls 17 whose diameter is such that the rolls will, as hereinafter explained, wedge within the narrow portions of these ways so as to lock together the driving block 10 and the clutch member 15. Immediately behind these rolls 17 are follower rolls 18 which contact the rolls 17 throughout their length, and these rolls 18 are backed by two coil springs 19 whose rear extremities impinge against the adjacent stubs 16. The object of employing these follower rolls is to insure a constant and uniform pressure against the rolls 17 so that the latter will not tilt 15 sidewise, and the employment of two springs that contact the rolls 18 near the opposite ends of the latter renders the pressure of the rolls 18 even and constant.

By the employment of the comparatively long rolls 17 a more extended contact with the driving block and clutch member is brought about, but without the follower rolls these rolls 17 would readily tilt sidewise, particularly if a single spring were 25 employed between the same and the stubs, and this would, of course, in a short time render the device useless.

Since the long contact is insured by these rolls 17 as above set forth, only one pair of 30 these rolls is necessary, whereas if the ordinary short rolls were used their number would have to be greatly increased in order to obtain an aggregate frictional contact of sufficient extent.

25 20 is the driving crank with which connection is made from any reciprocating part of the engine, and this crank terminates at the lower end in a plate 21 having an outwardly projecting hollow hub 22 which latter fits loosely around the outer extremity of the shaft 9.

Extending from the rear of the plate 21 are two pins 23, 24, the former being stationary while the latter is adjustable 45 throughout an arcuate slot 25 within the plate. These pins, when the plate is in position with the hub 22 over the shaft 9, extend within the ways *b*, *d*, so that during the reciprocations of the crank 20 said pins will 50 strike against the walls of the adjacent stubs 16 to effect the revolution of the shaft 9 in the manner now to be described.

Presupposing the pin 24 to be adjusted so as to stand at the extreme lower end of the 55 slot 25 as is shown at Fig. 1, while the pin 23 is diametrically opposite, and referring particularly to Fig. 1, the movement of the crank toward the left will cause both pins to travel idly throughout the ways *b*, *d*, until they strike against the stubs 16 toward which they approach, and when they strike these stubs they will cause the member 15 to be rotated toward the left so as to bring the other two stubs within the range of the pins on the 60 return movement of the crank, which opera-

tion is very simple and ordinary and is not of the essence of my invention. This movement of the member 15 toward the left will draw the narrow portions of the ways *a*, *c*, away from the rolls 17, and therefore there will be no wedging action between the member 15 and the block 10, but on the return movement of the crank, when it swings toward the right, the block 10 and member 15 will be instantly locked together by the medium 75 of the rolls 17 and will therefore revolve in harmony, so that when the pins strike the walls of the stubs the rotation of the shaft 9 will be effected.

The adjustment of the pin 24 in the position shown at Fig. 1 will adapt the improvement to a very long stroke and at the same time will effect the minimum intermittent rotation of the shaft 9, so that a very small amount of oil will be constantly supplied 80 through the delivery pipe 26.

The maximum intermittent rotation of the shaft 9 will be brought about by adjusting the pin 24 so that it would stand at the upper end of the slot 25, so that these pins 90 would readily clamp or embrace two adjacent stubs 16, and therefore there would be no lost motion whatever between the crank and the member 15, and this position of parts would provide for a maximum feed of 95 oil. Of course, it will be readily understood that the intermittent rotation of the shaft 9 may be governed as to its extent by the adjustment of the pin 24, the stroke of the engine being, of course, taken into consideration.

It will be readily understood that the elongated opening 5, the finger 6, the screw 7, and lock nut 8, hereinbefore described, are not necessary for the purpose of regulating 105 the rotation of the shaft 9, but are merely necessary, in connection with the present invention, in order to communicate motion from the cam slide 3 to the piston 4.

In order that there may be no accidental revolution of the block 10, and consequently 110 the shaft 9, during the return movement of the crank, or, in other words referring to Fig. 1, a movement of the crank toward the left, I have provided a detent construction which 115 is housed within the recess 13 in the rear of the block 10 which construction as well as its operation, I will now describe.

Within the recess 13 in the driving block 10 and loosely journaled around the hub 11 120 is a detent member 27 which is securely anchored to the feed block 2 through the medium of a pin 28 which extends from said block within a hole 29 in said member, so that it will be clearly understood that the 125 latter will be incapable of rotary movement. The periphery of this member 27 is cut away preferably at diametrically opposite locations so as to provide ways *e*, and this cutting away is effected in such manner that 130

these ways taper at one end, such tapered portions extending in the same direction. The outer circumference of the member 27 conforms generally to the inner surface of the rim of the driving block 10, and the floors of the ways *e* are eccentrically disposed so that they form these tapered portions in conjunction with said surface. Within the ways *e* are short rolls 30 which are backed by springs 31 that impinge against the end walls of the ways *e* at their widest portions, and since these rolls are quite short single springs only are necessary.

On the return or passive movement of the crank 20, should there be any tendency of the driving block 10 to revolve in harmony with the driving clutch member 15, the rolls 30 will instantly wedge within the narrow portions of the ways *e*, and since the member 27 is rigid, the block 10 during such passive movements of the crank will be held absolutely stationary, and this is very advantageous since reverse movements of the driving block will cause corresponding movements of the shaft 9 which would interfere seriously with the proper feed of the oil, and, moreover, unnecessary wear of the parts is eliminated. The usual hand crank 32 is provided and is screwed on the end of the shaft 9, so that the shaft may be rapidly revolved by hand at any time in order to supply considerable quantities of oil in a short period of time should the occasion demand.

It is customary to place a given quantity of oil within the reservoir 1, and after the intermittent revolution of the shaft 9 has been regulated, it is, of course, a simple matter to determine how long the supply of oil will last, and therefore it is not at all necessary that the engineer should keep the lubricator under constant supervision. The level of the oil is ascertained from the gage glass 47 which extends within and is supported from the reservoir 1 by the sockets 33, 34. The glass is held against dislodgment by screw 48 threaded in the upper socket 33, while the lower side of socket 34 is closed by a screw 38 as shown in Fig. 1.

Having thus described my invention what I claim as new and desire to secure by Letters Patent is:—

1. In a force feed lubricator, the combination with a stationary feed block, of an actuating shaft, a driving block secured to the shaft, a driving clutch member so formed in conjunction with the driving block as to provide a tapering way, a clutch roll arranged within the way to clutch the driving block and member for movement in one direction, a clutch detent carried by the feed block and arranged to clutch the driving block on reverse movement thereof to disengage the clutch roll from the driving block, and means for operating the driving clutch member.

2. In a force feed lubricator, the combination of the actuating shaft, a driving block secured thereto, a driving clutch member carried by said block for clutching the latter and driving it in one direction only, said member having free and independent reverse movement, an operating crank connected to said member, and a clutch detent member carried by said block for clutching the latter on the reverse movements of the driving clutch to disengage the latter from the block.

3. In a force feed lubricator, the combination of the actuating shaft, a partitioned driving block secured thereto and provided by said partition with shallow and deep interior recessed portions, a driving clutch member journaled within the deep recess and so formed in conjunction with the inner rim surface of said block as to provide tapering ways, elongated clutch rolls within said ways, elongated spring impelled follower rolls in contact with said clutch rolls, an operating crank connected to said member, a detent clutch member journaled within the shallow recess and having in its perimeter cut away portions which in conjunction with the inner rim of said block form tapering ways, rolls within the latter, and means for holding said detent clutch stationary as to rotation.

4. In a force feed lubricator, the combination of the actuating shaft, a driving block having a hub that is secured to said shaft, a driving clutch member journaled within the outer face of said block and surrounding said hub, tapering ways formed by the inner rim of said block and by cut away portions in the circumference of said member, spring impelled clutch rolls within said ways, elongated diametrically opposite openings within said member, and a driving crank loosely supported around the outer end of said shaft and having pins which extend within said openings for limiting the movement of the crank relative to the clutch member.

5. In a force feed lubricator, the combination of the actuating shaft, a driving block having a hub that is secured to said shaft, a driving clutch member journaled within the outer face of said block and surrounding said hub, tapering ways formed by the inner rim of said block and by cut away portions in the circumference of said member, spring impelled clutch rolls within said ways, elongated diametrically opposite openings within said member, and a driving crank loosely supported around said shaft and having a stationary driving pin and an adjustable driving pin which pins extend respectively within said openings.

6. In a force feed lubricator, the combination of the actuating shaft, a driving block having a hub that is secured to said

shaft, a driving clutch member journaled within the outer face of said block and surrounding said hub, tapering ways formed by the inner rim of said block and by cut 5 away portions in the circumference of said member, spring impelled clutch rolls within said ways, a stationary detent clutch member journaled within the rear face of said block and surrounding said hub, tapering ways formed by the inner rim of said 10 block and by cut away portions in the circumference of said detent member, spring impelled clutch rolls within the last named ways, elongated diametrically opposite openings within said member, and a driving crank loosely supported around the outer 15 end of said shaft and having pins which extend within said openings for limiting relative movement between the driving 20 clutch member and the crank.

7. In a force feed lubricator, the combination with a stationary feed block, of an

actuating shaft, a driving block secured to the shaft and having its opposite faces recessed, a driving clutch member arranged 25 in one recessed face of the driving block and so formed in conjunction with the latter as to provide a tapering way, a clutch element in the tapering way to clutch the driving block and clutch member for movement 30 in one direction only, means for operating the driving clutch member, a clutch detent arranged in the opposite recessed face of the driving block and so formed in conjunction with the latter as to provide a 35 tapering way, said clutch detent being secured to the feed block against rotary movement, and a clutch element in the tapering way provided by the clutch detent and driving block for clutching the two to hold the 40 driving block against reverse rotation.

In testimony whereof I affix my signature.

BERNARD H. SKELLY.
